(57) **CLAIM**

The ornamental design for an X-ray digital imaging device as shown and described.

DESCRIPTION

FIG. 1 is a top-side perspective view of an X-ray digital imaging device, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom-side perspective view; and,

FIG. 9 is an enlarged cross-sectional view along line 9-9 of portion 9'-9'.

The broken lines shown in the drawings of the X-ray digital imaging device and form no part of the claimed design.
